UNITED STATES PATENT OFFICE

2,474,693

MAGNETIC FIELD RESPONSIVE DEVICE

Robert G. Rowe, Niagara Falls, N. Y.

Application January 31, 1945, Serial No. 575,438

17 Claims. (Cl. 175—183)

1

This invention relates, in general, to magnetic field responsive devices and, in particular, to a novel and useful method and apparatus for indicating the magnitude and/or direction of magnetic fields or the deviation from the earth's magnetic meridian.

While the present invention is different in principle and character from other magnetic field responsive devices, it may be most closely compared with earth inductor compasses of a type known generally as magneto or flux gate compasses. Certain limited parallels of function can similarly be drawn between the present invention and United States Patent Number 2,331,617, issued on October 12, 1943, to David W. Moore, Jr.

Prior art compasses under the general classification of earth inductor compasses and, in particular, magneto compasses, require an oscillating or rotating member mounted in pivots or bearings and have the disadvantages of critical bearing tension, bearing wear, bearing adjustment and other faults resulting from frictional phenomena. In addition, magneto compasses have the further disadvantage of requiring an auxiliary driving motor device coupled to the generator being excited by the earth's field. These compasses suffer the disadvantages of high expense and complexity inherent in mechanical systems having numerous moving parts operating at high rotational speeds. Further, they require a means for commutation which introduces difficulties arising from commutator and brush wear. Still further, they produce low power outputs which are, in many cases, insufficient for control or for driving repeater compass indicators.

The magnetic field responsive device disclosed in United States Patent Number 2,331,617, while overcoming some of the disadvantages of prior art earth inductor compasses, still retains the disadvantage of requiring a delicate pivotally mounted oscillating member. In addition, a further disadvantage occurs due to the care which must be exercised in balancing the oscillating member with respect to the alternating current exciting winding.

Therefore, an object of the present invention is to provide a magnetic field responsive device, suitable for use in the earth inductor compass, which eliminates pivotally mounted oscillating parts.

Another object of the present invention is to provide a magnetic field responsive device, suitable for use in the earth inductor compass, which eliminates rotating parts.

2

Still another object of the present invention is to provide a magnetic field responsive device, suitable for use in the earth inductor compass, with which appreciable amounts of power may be produced.

A further object of the present invention is to provide a novel and improved magnetic field responsive device.

A still further object of the present invention is to provide a magnetic field responsive device which substantially overcomes one or more of the disadvantages of prior art earth inductor compasses.

The foregoing objects and other objects ancillary thereto I prefer to accomplish in short by a novel combination of the magneto-mechanical properties of ferromagnetic or magnetostrictive materials with electric detecting and/or indicating apparatus.

The novel features which I believe to be characteristic of my invention are engendered with particularity in the appended claims; the invention itself, however, will be best understood by reference to the accompanying detailed description and drawings, in which

Figure 1 illustrates graphically an approximate curve of the manner in which a magnetostrictive material changes length in a magnetic field.

Figure 2 illustrates graphically an expanded portion of the lower knee of the foregoing curve.

Figure 3 illustrates graphically an expanded portion of the upper knee of the foregoing curve.

Figure 4 illustrates diagrammatically and schematically one embodiment of the present invention.

Figure 5 illustrates diagrammatically and schematically another embodiment of the present invention.

Figure 6 illustrates diagrammatically and schematically a regenerative method for exciting natural elastic longitudinal vibrations in magnetostrictive material.

Figure 7 illustrates diagrammatically and schematically another regenerative method for exciting vibrations in magnetostrictive material.

Figure 8 illustrates diagrammatically and schematically still another embodiment of the present invention.

Figure 9 illustrates diagrammatically and schematically a further embodiment of the present invention.

Figure 10 illustrates diagrammatically and schematically still a further arrangement of the present invention.

With reference to the present invention in

general, magnetostriction refers to that set of phenomena in which certain materials exhibit a change in dimension upon magnetization.

With reference now to Figure 1, which illustrates an approximate curve *a-b-c-d-e-f-g-h* of the manner in which magnetostrictive material changes length in a magnetic field, *H* linearly represents the magnetic field intensity, *l* the original length of the material and *l_m* the modified length of the material due to field *H*. Hence

$$\frac{l_m - l}{l}$$

linearly represents the change in length per unit length of material in field *H*. It will be appreciated that *l_m* may be either greater or smaller than *l*, depending upon the nature of the material and, for some materials, upon the field intensity. Nickel only shortens upon magnetization; cobalt shortens for low field intensities and lengthens for high; iron lengthens for low field intensities and shortens for high; certain manganese alloys only lengthen upon magnetization.

With reference to Figures 2 and 3, which illustrate expanded portions of the curve in Figure 1, the primed letters refer to *H* values and the double primed letters refer to

$$\frac{l_m - l}{l}$$

values for the correspondingly lettered points on the curve. Inspection of Figures 1, 2 and 3 reveals that the slope of the magnetostriction curve,

$$\Delta \left(\frac{l_m - l}{l} \right) / \Delta H$$

is not a constant. For example, the change in length attendant upon a unit increase in *H* from point *a'* to point *b'* is smaller than that produced by unit increase in *H* from point *c'* to point *d'*. Similarly, the change in length attendant upon unit increase in *H* from point *e'* to point *f'* is greater than that produced by unit increase in *H* from point *g'* to point *h'*. Thus, for unit increase in *H*, *a''b''* is smaller than *b''c''*; *b''c''* is smaller than *c''d''*; and so on. The same is true for decreasing *H* values beginning at point *d* on the curve. A similar relationship can be worked out for the upper knee of the curve as shown in Figure 3.

From the above disclosure it will be recognized that if a rod of ferromagnetic or magnetostrictive material where suspended in the field of the earth, for example, the length of the rod would change in accordance with its position in the field. If the longitudinal axis of the rod were perpendicular to the earth's field, that is in an east-west direction, *H* along the axis of the rod would be substantially zero and hence no change in length would occur. Displacing the longitudinal axis of the rod in a manner such that it becomes parallel to the earth's field, that is in a north-south direction, *H* along the axis of the rod would become greater than zero and a change in length would obtain. The change in length attending magnetization by weak fields such as that of the earth is so exceedingly minute, however, that rugged mechanical means for indication of dimensional modification would be difficult to design and construct. Vibration, thermal effects and other difficulties make mechanical methods impractical due to their delicate nature.

I have found that when I partially magnetize and then further impress upon the rod an alter-

nating magnetic field in addition to the steady field under observation, and that when I match the periodicity of the alternating field with some harmonic of a natural elastic longitudinal period of the rod, I am able to indicate changes in the direction or magnitude of the steady field under observation by measuring the change in the resonant amplitude of vibration of the rod.

For example, with reference to Figure 2, assume that a rod of ferromagnetic or magnetostrictive material has been sufficiently magnetized to give an *H* value of *b'*. An alternating magnetic field can be applied in addition such that the total value for *H* will fluctuate around *b'* from *b'* to *c'*, from *c'* back through *b'* to *a'*, from *a'* to *b'* and so on, at the frequency of the A. C. field. Operation will be over a portion of the curve where the change in length per unit length attending these combinations of fields is relatively small and might be represented by a change from *a''* to *c''*.

Now assume that an additional steady field which aids the pre-magnetized condition of the rod is added such that *H* has a new value corresponding to *c'*. An alternating magnetic field can be added such that the total value for *H* will fluctuate around *c'* from *c'* to *d'*, from *d'* back through *c'* to *b'*, from *b'* to *c'* and so on, at the frequency of the A. C. field. Operation will be over a portion of the curve where the change in length per unit length attending this new combination of fields is greater than in the previous case and might be represented by a change from *b''* to *d''*.

When the frequency of the applied alternating magnetic field is closely matched to that of a natural elastic longitudinal period of the rod, resonance occurs between the electrical and mechanical systems and the amplitude of rod displacement becomes large enough to detect electrically. Setting the center operating point by pre-magnetization at *b*, on the curve in Figure 2, produces a certain vibrational amplitude in the rod; whereas setting the center operating point at *c*, on the curve in Figure 2, produces a greater vibrational amplitude.

I have found that steady magnetic fields of low intensity, such as the earth's field, are of sufficient magnitude to shift the operating point on the curve and that I can detect this shift by electrical and/or electronic means due to the resulting change in the vibrational amplitude of the rod. In Figures 1 and 3, curve *e-f-g-h* has been included to illustrate the possibility of operation at a different center point on the large curve. For improved indicator linearity or sensitivity it may be desirable to operate over this portion. It is to be understood that all ferromagnetic or magnetostrictive materials do not exhibit the same magnetostrictive curve and that it remains to select that material best suited to desired operating conditions.

It is to be understood, further, that I do not wish to be limited to the detection of variations in vibrational amplitude alone for an indication of the direction or magnitude of the external field. Later I show and describe methods and apparatus for the detection of phase angle shift, waveform distortion and other pertinent factors.

For a complete understanding of the nature of the present invention as opposed to certain other inventions, it is essential to comprehend the difference between introducing vibrations in a magneto-mechanical system by magnetostriction as opposed to introducing vibrations in a magneto-

mechanical system by magnetic attraction. In magnetostriction, the periodic field causes periodic changes in the dimension of the magnetostrictive element due to the periodic internal stress attending periodic magnetization by the field coil. In magnetic attraction, the periodic field causes changes in position of the magnetic armature element due to the periodic attraction between the armature and the field coil. In magnetostriction, the field coil may be conveniently wound directly on the magnetostrictive element; whereas in magnetic attraction, the field coil must be accurately spaced from the magnetic armature.

With reference now to Figure 4, magnetostrictive rod 1 is firmly clamped at its midpoint by supports 2 and 3. Exciting winding 4, which may be wound directly on the rod, is coupled through leads 5 and 6 to a source of alternating current of proper frequency. The frequency of the source of alternating current matches the natural mechanical longitudinal period of vibration of the rod at either its fundamental or some other harmonic period, in one embodiment of the invention. In this modification of the invention rod 1 may be made of annealed steel approximately ten inches long by one-half inch in diameter, and driven in resonance at its lowest natural longitudinal period by an A. C. source of approximately 10 kilocycles per second. The natural period of such a rod may be represented by the equation:

$$F = \frac{1}{2l} \sqrt{\frac{E}{d}}$$

where F equals the frequency in cycles per second, l equals the length in centimeters, E equals the modulus of elasticity in dynes per square centimeter and d equals the density of the rod material in grams per cubic centimeter.

In Figure 4, battery 7, rheostat 8 and winding 9, which may be wound directly on the rod as well, cooperate to apply slight pre-magnetization to rod 1. In practice I have found that this pre-magnetization may be that of a permanent nature and elements 7, 8 and 9 may be dispensed with if desirable. Piezoelectric transducer 10, which is mechanically connected to rod 1, may be of the Rochelle salt type and is further electrically coupled to input terminals 11 and 12 of amplifier 13. Amplifier 13 is designed, in this modification of the invention, to pass a narrow band of frequencies around 10 kilocycles and attenuate other frequencies. Such amplifiers are well known in the electronic art. Amplifier output terminals 14 and 15 are coupled through rectifier 16 and potentiometer 20 to indicating meter 17. Resistor 18, battery 19 and potentiometer 20 cooperate to supply a bucking voltage to meter 17 to buck out the initial meter deflection caused by the alternating current output of amplifier 13.

Rod 1, being slightly pre-magnetized by battery 7, rheostat 8 and coil 9, is set into resonant longitudinal vibration by an alternating excitation voltage applied across terminals 5 and 6. The mechanical output of the rod is converted into an alternating voltage by transducer 10 and this A. C. voltage is further amplified by amplifier 13. The output of amplifier 13 is rectified and applied through a balancing circuit to meter 17. The combination of resistor 18, battery 19 and potentiometer 20 is so proportioned that the initial deflection of meter 17 can be balanced to zero if desired.

With the apparatus disclosed, I have found that

I am able to indicate the direction and relative intensity of magnetic fields with respect to the longitudinal axis of rod 1.

When rod 1 is so oriented with respect to a magnetic field, for example the earth's field, in a manner such that the external field is aiding the pre-magnetized condition of rod 1, the amplitude of longitudinal vibration in the rod will increase and meter 17 will deflect from its balanced position due to the increased voltage output from transducer 10, amplifier 13 and rectifier 16. Conversely, when the external magnetic field is bucking the pre-magnetized condition of rod 1, the amplitude of longitudinal vibration in the rod 15 will decrease and meter 17 will deflect in a different direction from its balanced position due to reduced voltage output from transducer 10, amplifier 13 and rectifier 16.

Thus, by permitting the longitudinal axis of rod 1 to swing 360 degrees in a horizontal plane parallel to the surface of the earth, the direction of the earth's horizontal field may be indicated. Similarly, by fixing the longitudinal axis of the rod parallel with the keel line of a mobile vessel, 25 the direction of the vessel with respect to the earth's magnetic meridian may be determined. Further, a mounting may be provided such that the rod is always substantially exposed to only the horizontal component of the earth's magnetic 30 field, for installations in airships, or the like, having three axes of gyration. Mountings may be pendulously or "gyro" stabilized, if desired. Such mountings are old in the art of earth inductor compasses.

35 I have found, further, that the phase of the voltage produced by the longitudinal vibration of rod 1 can be caused to shift with respect to the phase of the exciting voltage, according to the condition of pre-magnetization, the frequency relationship between the driving source and the natural elastic period of the rod and the influence of weak external fields. With reference to Figure 10, the correspondingly numbered parts are explained in connection with Figure 4. In Figure 10, the exciting voltage appearing across terminals 5 and 6 is applied to input terminals 21 and 22 of amplitude limiter 23, as well as to coil 4 of rod 1. Output terminals 24 and 25 of limiter 23 are coupled to one pair of phase meter input terminals 26 and 27. The voltage output of amplifier 13 is similarly fed to input terminals 28 and 29 of amplitude limiter 30, and the limiter output, in turn, is fed from terminals 31 and 32 to the second pair of phase meter input terminals 33 and 34.

55 Amplitude limiters 23 and 30 are well known in the electronic art and are employed in this connection to prevent changes in voltage amplitude from effecting the phase meter. Phase meter 35 is likewise well known in the electronic art and includes a meter and suitable circuit for indicating the difference in phase or the change in phase between two input voltages of equal frequency and constant amplitude. In place of the apparatus indicated, other phase responsive devices may be suitably employed. In this modification, the frequency of the driving source closely matches the natural elastic period of the rod. With rod 1 perpendicular to the lines of force 60 of the external field, phase meter 35 will indicate a certain relationship between the phase of the driving source and the phase of the transducer voltage. With rod 1 parallel to the lines of force of the external field, phase meter 35 will indicate 65 a different relationship between the two voltages.

The phase shift can be utilized in this fashion to indicate the direction or magnitude of the external field.

Figure 5 illustrates a further modification of the invention employing a type of bridge circuit in which two oppositely pre-magnetized magnetostrictive rods are incorporated. Rods 36 and 37 are nodally clamped for a preferred mode of longitudinal vibration by supports 38, 39, 40 and 41 respectively. These supports are further mechanically connected together to keep the two magnetostrictive rods parallel and in the same plane at all times. In this particular embodiment of the invention, rods 36 and 37 are cut to accurately equivalent dimensions in order that both will exhibit elastic resonance at one and the same frequency. Exciting windings 42 and 43 are coupled through leads 44 and 45 to a source of alternating current of the proper frequency. In this modification of the invention, the exciting frequency may be equal to the natural fundamental longitudinal period of the rods.

Battery 46, rheostat 47 and windings 48 and 49 cooperate to oppositely pre-magnetize rods 36 and 37 as indicated. Piezoelectric transducers 50 and 51, which are mechanically connected to rods 36 and 37, have their outputs connected through amplifiers 52 and 53 to half-wave vacuum tube rectifiers 54 and 55. Rectifiers 54 and 55, filter condensers 56 and 57 and potentiometer 58 cooperate to supply a D. C. voltage for indicating meter 59.

Rods 36 and 37, being oppositely pre-magnetized, are set into resonant longitudinal vibration by an alternating excitation voltage applied across terminals 44 and 45. The mechanical output of the rods is converted into an alternating current by transducers 50 and 51 and passed through amplifiers 52 and 53 respectively. The output of each amplifier is separately rectified by rectifiers 54 and 55, filtered by condensers 56 and 57 and applied across potentiometer 58. With the longitudinal axes of rods 36 and 37 perpendicular to an external magnetic field, a point can be found by varying the sliding contact on potentiometer 58 at which no voltage will appear across meter 59.

With rods 36 and 37 so oriented with respect to an external magnetic field such that the field is aiding the pre-magnetized condition of rod 36 and simultaneously bucking that of rod 37, the amplitude of vibration of rod 36 will increase and that of rod 37 will decrease. The voltage output of transducer 50, amplifier 52 and rectifier 54 will increase, whereas the voltage output of transducer 51, amplifier 53 and rectifier 55 will decrease. This difference in voltage appearing across the previously balanced ratio arms of the bridge will cause meter 59 to deflect, for example to the right.

Conversely, with rods 36 and 37 so oriented with respect to the external magnetic field that the field is bucking the pre-magnetized condition of rod 36 and simultaneously aiding that of rod 37, the amplitude of rod 36 will decrease and that of rod 37 will increase. The voltage output of transducer 50, amplifier 52 and rectifier 54 will decrease, whereas the voltage output of transducer 51, amplifier 53 and rectifier 55 will increase. This reverse difference in voltage appearing across the previously balanced ratio arms of the bridge will cause meter 59 to deflect in a reverse direction, or to the left.

Thus, when the longitudinal axes of rods 36 and 37 are parallel to the flux lines of the external

magnetic field, meter 59 will give a maximum deflection either to right or left according to the polarity of the external field. When rods 36 and 37 have their longitudinal axes perpendicular to the flux lines of the external magnetic field, meter 59 will not deflect from its normal center position. It is to be understood that other suitable forms of metering may be employed. The balanced or bridge type of circuit briefly described and illustrated in Figure 5 has several advantages, some of the more important being that it tends to exhibit improved linearity and stability. It will be obvious that phase responsive as well as amplitude responsive detecting, correlating and indicating means may be employed. In phase responsive systems it may be further desirable to adjust the natural elastic period of one rod to be slightly higher and that of the other rod to be slightly lower than the period of the exciting frequency.

Figure 6 illustrates a regenerative means to excite longitudinal vibrations in a rod by the phenomenon of magnetostriction and is well known in the art of magnetostriction generators. With reference to Figure 6, magnetostrictive rod 60 is firmly clamped at its nodal midpoint by supports 61 and 62. Windings 63 and 64 are grid and plate windings for vacuum tube 65. Condenser 66 is chosen to resonate coil 64 at the desired operating frequency, which is the resonant frequency of rod 60. Rod 60 provides a magneto-mechanical regenerative feedback path between the plate and grid circuits of vacuum tube 65 and the circuit can be made to oscillate at the natural elastic period of the rod. Pre-magnetization of rod 60 is accomplished by the steady plate current flow through coil 64 supplied by battery 67. It is to be understood that rod 60 may likewise be coupled to a transducer and that subsequent circuits for detecting, correlating and indicating amplitude, phase or waveform change may be employed. It is to be understood further that currents within the regenerative circuit will be modified by the direction and magnitude of the external magnetic field and that circuits for indicating these modifications may be used. Such circuits are well known in the electronic art and, for example, conveniently may be represented by meter M are not repeated for the sake of brevity.

Figure 7 illustrates another regenerative means to excite longitudinal vibrations in a rod by the phenomenon of magnetostriction. With reference to Figure 7, magnetostrictive rod 68 is nodally clamped by supports 69 and 70. Battery 71, rheostat 72 and coils 73 cooperate to pre-magnetize rod 68 to the desired value. Piezoelectric transducer 74 is coupled to amplifier 75 and the amplified output is returned to rod 68 through coils 76. In the manner well known to those versed in the art, the system oscillates at the natural elastic period of the mechanical feedback link, rod 68. It is to be understood that similar circuits for detecting amplitude, phase and waveform changes occasioned by the magnitude or direction of an external magnetic field may be employed. The circuits illustrated in Figures 6 and 7, that is regenerative driving circuits for the magnetostrictive element, have the advantage that resonance is always maintained between the natural elastic period of the magnetostrictive element and the exciting voltage. Changes in rod length due to thermal effects are thus compensated.

As previously explained, when rods of certain materials are introduced into a magnetic field they suffer a change in length. For example, a

nickel rod will become shorter, the change in length being proportional to the intensity of the magnetic field and not upon the polarity of the field. When a nickel rod is introduced into an alternating magnetic field, such as that produced by a solenoid excited with a periodic or an alternating current, the rod will be shortened periodically by the periodic magnetization. If an unmagnetized nickel rod is introduced into an alternating current magnetic field, it will become shorter twice during each cycle of the exciting field's frequency and will thus vibrate with twice the frequency of the exciting field. When a permanent magnetic field is superimposed upon the longitudinal axis of the rod, in addition to the alternating field, the rod will tend to vibrate at the frequency of the exciting field rather than at twice the frequency.

For example, a rod approximately ten inches long has a fundamental elastic period of longitudinal vibration of approximately 10 kilocycles. When such a rod is not permanently or otherwise pre-magnetized and is introduced into a 10 kilocycle alternating magnetic field, it will tend to vibrate at twice its fundamental elastic period or 20 kilocycles. This corresponds to the second harmonic of the fundamental elastic period of the rod. As a permanent magnetic field is applied to the longitudinal axis of the rod, its 20 kilocycle output will diminish and its 10 kilocycle output will increase.

Figure 8 illustrates another modification of the present invention incorporating this principle. Magnetostrictive rod 71 may be supported by clamps 78 and resilient material 79. A method of mounting is preferred which will permit both first and second harmonic vibration. Exciting winding 80 is coupled through leads 81 and 82 to a source of alternating current which has a period closely matching the fundamental elastic period of rod 71. Transducer 83, which is mechanically connected to rod 71, is further electrically connected to input terminals 84 and 85 of amplifier 86. Amplifier output terminal 87 is grounded and terminal 88 is connected through resistors 89 and 90 to two tuned filter circuits. Coil 91 and condenser 92, excited through resistor 89 and ground, are tuned to the fundamental period of rod 71 and the output of this portion of the circuit is coupled through rectifier 93 to one half of the bridge metering circuit comprising potentiometer 94 and filter condenser 95. Coil 96 and condenser 97, excited through resistor 90 and ground, are tuned to the second harmonic of the fundamental period of rod 71 and the output of this portion of the circuit is coupled through rectifier 98 to the remaining half of the bridge metering circuit comprising potentiometer 94 and filter condenser 99. Indicating meter 100 is connected across potentiometer 94 as shown in previous modifications.

With the longitudinal axis of unmagnetized rod 71 perpendicular to the lines of force of an external magnetic field, the rod is set into resonant longitudinal vibration by an exciting voltage equal in frequency to the natural elastic period of the rod. Rod 71 vibrates at twice its fundamental elastic period, or the second harmonic. Transducer 83 transforms this mechanical motion into a voltage of equivalent periodicity, which is amplified by amplifier 86 and passed through resistor 90, filter circuit 27 and rectifier 98 to potentiometer 94 and condenser 99, unbalancing the bridge and causing meter 100 to deflect in one direction. As the longitudinal axis of unmag-

nized rod 71 is caused to become more nearly parallel to the lines of force of an external magnetic field, the 10 kilocycle output of the rod increases and the 20 kilocycle output decreases. This change is detected by transducer 83, amplifier 86 and filter circuit 27, causing more voltage to appear across condenser 95 and less to appear across condenser 99, further causing meter 100 to deflect in the reverse direction.

- 10 Figure 9 illustrates a further modification of the present invention incorporating the foregoing principle, with rod 101 supported by clamps 102 and resilient material 103. A method of mounting is preferred which will permit both fundamental and harmonic vibration. Exciting winding 104 is coupled through leads 105 and 106 to a source of alternating current having a period closely matching that of the natural elastic fundamental period of rod 101. In this embodiment of the invention, rod 101 may be pre-magnetized slightly as will be later explained. Such pre-magnetization may be permanent or electromagnetically induced as discussed in connection with previous embodiments. Transducer 107, mechanically coupled to rod 101, is further electrically connected through harmonic wave analyser 108 to harmonic content meter 109. Circuits for analysing the harmonic content of waveforms are well known in the electronic art and such instruments for indicating harmonic content directly are commercially available. Harmonic wave analyzer 108 and harmonic content meter 109 are found commercially in the model 300-A Harmonic Wave Analyzer produced by the Hewlett-Packard Company of Palo Alto, California.
- 15 With slightly magnetized magnetostriction rod 101 excited by an alternating field equal in frequency to the fundamental elastic period of rod 101, transducer 107 will generate a voltage which will contain predominantly a sine wave of the fundamental longitudinal elastic period of the rod. When a steady external magnetic field is applied along the longitudinal axis of the rod such that it is bucking the pre-magnetized condition of the rod, the voltage output from transducer 107 will exhibit a wave shape containing the fundamental plus a second harmonic component. The harmonic wave analyser will detect these differences and the meter of the wave analyzer circuit may be calibrated in terms of the direction and/or magnitude of the magnetic field surrounding the rod.
- 20

- 25 The operation connected with Figure 9 can be explained best by reference again to Figure 3. For example, the rod is pre-magnetized such that the value of H falls at a' . An alternating magnetic field may be applied which will cause the value of H to shift from a' to b' , from b' back through a' to zero, from zero to a' , and so on, at the frequency of the exciting voltage. When another steady magnetic field is simultaneously applied, as the earth's field for example, the operating point a may move closer to the vertical axis. One half of the exciting field cycle will attempt to reduce H to zero and, in doing so, will move beyond zero, causing H to increase slightly. This phenomenon will introduce a second harmonic component in the waveform from the transducer and this component may be detected by means similar to that disclosed or some equivalent thereof. By controlling the pre-magnetization, the appropriate center operating point on the curve in Figure 2 may be selected for desired operating characteristics.

- 70

As explained earlier in this disclosure certain materials, for example iron, lengthen for low field intensities and shorten for higher field intensities. Thus, a point exists on the magnetostriction curve for this material such that an increase in the field intensity H will cause the rod to lengthen and a further increase in H will cause the rod to shorten. For convenience, assume this point to be the "critical deflection" point. It will be apparent to those versed in the art that this point may be selected as the center operating point and that, as a change in H causes the center operating point to shift along the curve, there will follow a change in phase between the exciting and output voltages as the operating point passes through the zero deflection point.

Further, because magnetization changes the dimensions of certain materials, it also shifts the natural elastic period of vibration of these materials. It is obvious that means responsive to the change in natural period may be employed to detect and indicate the influence of the external field under observation. Such means may include a modified discriminator circuit familiar to those versed in the electronic art.

It will be appreciated that, if desired, the magnetostrictive element may be supplied with an electro-mechanical or servo system responsive to its output to keep it oriented in any desired position with regard to the external field. Such systems are well known in the arts of electronics and navigation.

Further, it will be appreciated that certain benefits will accrue through the selection of magnetostriction elements having particularly suitable elastic, magnetic and other physical properties. Still further, the system allows a wide choice as to operational frequency over the sonic and ultrasonic range. Equipment may be designed which is not detrimentally effected by the usual lower frequency vibrations.

While I have shown and described in detail several preferred embodiments of my invention, I am aware that various changes and modifications may occur to those versed in the art without departing from the invention. Therefore, it is aimed in the appended claims to cover any and all such changes and modifications which fall within the true spirit and scope of the invention. 50

I claim:

1. In a magnetic field responsive device, a magnetostrictive element nodally supported for a preferred mode of substantially undamped vibration, coil means excited from a constant frequency source of periodically varying voltage and magnetically linked with said element to magnetostrictively vibrate said element, detector means coupled to said element sensible to variances in the characteristics of magnetostrictive vibrations of said element and indicator means coupled to said detector means arranged to indicate variances in the characteristics of magnetostrictive vibrations of said element. 60

2. In a magnetic field responsive device, a magnetized magnetostrictive element nodally supported for a preferred mode of substantially undamped vibration, coil means excited from a constant frequency source of periodically varying voltage and magnetically linked with said element to magnetostrictively vibrate said element, detector means coupled to said element sensible to variances in the characteristics of magnetostrictive vibrations of said element and indicator means coupled to said detector means arranged 70

to indicate variances in the characteristics of magnetostrictive vibrations of said element.

3. In a magnetic field responsive device, a magnetostrictive element nodally supported for a preferred mode of substantially undamped vibration, means independent of ambient magnetic fields to magnetize said element, coil means excited from a constant frequency source of periodically varying voltage and magnetically linked with said element to magnetostrictively vibrate said element, detector means coupled to said element sensible to variances in the characteristics of magnetostrictive vibrations of said element and indicator means coupled to said detector means arranged to indicate variances in the characteristics of magnetostrictive vibrations of said element. 15

4. In a magnetic field responsive device, a magnetized magnetostrictive element, nodally supported for a preferred mode of substantially undamped vibration, coil means excited from a constant frequency source of periodically varying voltage and magnetically linked with said element to magnetostrictively vibrate said element and detector means, coupled to said element, arranged to indicate variances in the amplitude of magnetostrictive vibrations of said element. 20

5. In a magnetic field responsive device, a magnetized magnetostrictive element nodally supported for a preferred mode of substantially undamped vibration, coil means excited from a constant frequency source of periodically varying voltage and magnetically linked with said element to magnetostrictively vibrate said element and detector means, coupled to said element, arranged to indicate variances in the phase of magnetostrictive vibrations of said element. 25

6. In a magnetic field responsive device, a magnetostrictive element supported for at least two preferred modes of substantially undamped vibration, coil means excited from a constant frequency source of periodically varying voltage and magnetically linked with said element to magnetostrictively vibrate said element and detector means, coupled to said element, arranged to indicate variances in the waveform of magnetostrictive vibrations of said element. 40

7. In a magnetic field responsive device, a magnetostrictive element nodally supported for a preferred mode of substantially undamped vibration, coil means excited from a constant frequency source of voltage periodically varying at a frequency attuned to a natural period of vibration of said element and magnetically linked with said element to magnetostrictively vibrate said element and detector means, coupled to said element, arranged to indicate variances in the characteristics of magnetostrictive vibrations of said element. 55

8. In a magnetic field responsive device, a magnetostrictive element nodally supported for a preferred mode of substantially undamped vibration, coil and circuit means magnetically linking said element arranged to include said element as a magneto-mechanical feedback path in a regenerative electrical circuit, regenerative electrical circuit means coupled to said coil means and means, coupled to said circuit means, arranged to indicate variances in the characteristics of magnetostrictive vibrations of said element. 60

9. In an earth inductor compass, a magnetostrictive element nodally clamped for a preferred mode of substantially undamped vibration, means

supporting said clamping means for angular movement of said element relative to the earth's magnetic field, means independent of the earth's magnetic field to magnetize said element, coil means excited from a constant frequency source of periodically varying voltage and magnetically linked with said element to magnetostriictively vibrate said element and detector means, coupled to said element, arranged to indicate variances in the characteristics of magnetostrictive vibrations of said element as influenced by the earth's magnetic field, whereby the direction of the earth's magnetic meridian may be determined.

10. In a magnetic field responsive device, a magnetostrictive element, nodal clamping means arranged to support said element for substantially undamped vibrations and for angular movement relative to an ambient magnetic field, means independent of said ambient magnetic field to magnetize said element, coil means excited from a constant frequency source of periodically varying voltage and magnetically linked with said element to magnetostriictively vibrate said element and detector means, coupled to said element, arranged to indicate variances in the characteristics of magnetostrictive vibrations of said element as influenced by the direction of said ambient magnetic field.

11. The method of detecting and indicating the magnitude and direction of a magnetic field comprising, subjecting a magnetostrictive element simultaneously to a first magnetic field to be detected and a second alternating magnetic field of predetermined magnitude, direction and frequency and detecting and indicating the variance in the characteristics of magnetostrictive vibrations of said magnetostrictive element as influenced by the magnitude and direction of the magnetic field to be detected and indicated.

12. The method of detecting and indicating the magnitude and direction of a magnetic field comprising, subjecting a magnetostrictive element simultaneously to a first magnetic field to be detected, a second steady magnetic field of predetermined magnitude and direction and a third alternating magnetic field of predetermined magnitude, direction and frequency and detecting and indicating the variance in the characteristics of magnetostrictive vibrations of said magnetostrictive element as influenced by the magnitude and direction of the magnetic field to be detected and indicated.

13. The method of detecting and indicating the magnitude and direction of a magnetic field comprising, immersing a magnetostrictive element in the field to be detected, magnetostriictively vibrating said magnetostrictive element and detecting and indicating the variance in the characteristics of magnetostrictive vibrations of said element as influenced by the magnitude and direction of the magnetic field to be detected and indicated.

14. The method of detecting and indicating the magnitude and direction of a magnetic field comprising, immersing a magnetostrictive element in the field to be detected, superimposing

on said element a steady magnetic field of predetermined magnitude and direction, superimposing on said element an alternating magnetic field of predetermined magnitude, direction and frequency and detecting and indicating variances in the characteristics of magnetostrictive vibrations of said element as influenced by the magnetic field to be detected and indicated.

15. The method of detecting and indicating the magnitude of a magnetic field comprising, immersing a magnetostrictive element with a predetermined orientation in the magnetic field to be detected, magnetically biasing said magnetostrictive element with a second magnetic field, magnetostriictively vibrating said magnetostrictive element with a third periodically varying magnetic field, detecting and indicating the characteristics of magnetostrictive vibrations of said element, varying the magnitude of the field to be detected and simultaneously detecting and indicating the variance in the characteristics of magnetostrictive vibrations of said element.

16. The method of detecting and indicating the direction of a magnetic field comprising, immersing a magnetostrictive element in the field to be detected, magnetically biasing said element with a second magnetic field, magnetostriictively vibrating said element with a third periodically varying magnetic field, detecting and indicating the characteristics of magnetostrictive vibrations of said element, varying the direction of the field to be detected with respect to said element and detecting and indicating the variance in the characteristics of magnetostrictive vibrations of said magnetostrictive element.

17. The method of detecting and indicating the magnitude and direction of a magnetic field comprising, immersing a magnetostrictive element in the field to be detected, magnetostriictively vibrating said magnetostrictive element, detecting the characteristics of magnetostrictive vibrations of said magnetostrictive element, varying the position of said magnetostrictive element with respect to the magnetic field to be detected and indicated, and simultaneously detecting and indicating the variance in the characteristics of magnetostrictive vibrations of said magnetostrictive element as influenced by the magnitude and direction of the magnetic field to be detected and indicated.
